DESIGN FOR A KNITTED TEXTILE FABRIC

Morris Feldman, New York, N. Y.

Application August 26, 1935, Serial No. 58,291

Term of patent 3½ years

To all whom it may concern:

Be it known that I, Morris Feldman, a citizen of the United States of America, residing in Manhattan, county of New York, and State of New York, have invented a new, original, and ornamental Design for a Knitted Textile Fabric, of which the following is a specification, reference being had to the accompanying drawing, forming part thereof, wherein, the figure is a plan view of a piece of knitted textile fabric showing my new design.

The substantially rectangular motifs arranged in staggered relation with the substantially diamond shaped motifs are of a superimposed contrasting design woven over the tattered crocheted fabric.

I claim:

The ornamental design for a knitted textile fabric, substantially as shown and described.

MORRIS FELDMAN.
